KERF CUTTER FOR MINING APPARATUS

Original Filed Dec. 23, 1919 2 Sheets-Sheet 2

UNITED STATES PATENT OFFICE

EDMUND C. MORGAN, DECEASED, LATE OF NEW YORK, N. Y., BY OLIVA EUGENIE MORGAN, EXECUTRIX, OF NEW YORK, N. Y.

KERF CUTTER FOR MINING APPARATUS

Original application filed December 23, 1919, Serial No. 346,903. Divided and this application filed October 17, 1927. Serial No. 226,690.

This application is a division of the co-pending application of the same inventor filed December 23, 1919, Serial No. 346,903, for mining and loading apparatus and method of mining.

The present invention, while relating to the same general subject-matter as that of the above identified co-pending application, is more particularly concerned with the construction and operation of the kerf-cutter and its co-operative relationship with the mining apparatus referred to in said co-pending case.

The principal object of the present invention is to provide means for cutting a kerf in the side walls of a mine vein in advance of a dislodging apparatus which follows the kerf-cutter, and with the construction and operation of the kerf cutter so arranged that the same may be moved into an inactive position after the production of the kerf so as to leave an unobstructed line of movement for the dislodging apparatus, operation of which follows the kerf-cutter so as to dislodge the material cut by the kerf-cutter.

One of the objects of the invention is the provision of a kerf-cutter intermediate the floor and the roof of a mine chamber adjustable in elevation and inclination so as to adapt the same to the cutting out of partings or dirty bands in coal veins in various locations.

Another object of the invention is to provide a kerf-cutter which may be elevated and lowered relatively of the apparatus with which it is associated and which may be also adjusted on an incline relatively of the mine wall in which the kerf is to be made.

A still further object is to provide a kerf-cutter with means for adjusting the same on an incline, up or down, in the direction in which the dislodging apparatus is moved.

Still another important feature of the invention resides in the construction of the kerf-cutter which permits the same to be detachably mounted on a material-dislodging apparatus.

Another object of the invention is the provision of a kerf-cutter which is particularly adapted to the cutting of arcuate kerfs in the mine wall so as to facilitate the dislodgment

of the material by a material-dislodging apparatus associated with the kerf-cutter and mounted also for arcuate movement.

Other objects of the invention will appear hereinafter, the novel combinations and features being set forth in the appended claims.

Referring to the accompanying drawings—
Fig. 1 is a plan view of a loading machine combined with mining and kerf-cutting mechanism;

Fig. 2 is an elevational view of the combined mining and loading machine with a portion of the kerf-cutting mechanism included to show its relation to the other parts;

Fig. 3 is a plan view, partly in section, of a kerf-cutting mechanism the position of which, when not in use, being shown by the dotted lines at the upper right hand portion of Fig. 1;

Fig. 4 is a sectional elevational view taken on the line 4—4 of Fig. 3 looking in the direction of the arrows; and

Fig. 5 is a sectional detail view taken on the line 5—5 of Fig. 3 looking in the direction of the arrows.

In practice, the kerf-cutter is best adapted for use in combination with mining machinery of that class illustrated in Figs. 1 and 2. The particular apparatus shown in these figures forms a part of the above-identified co-pending application, and for a complete description of the construction and operation of such an apparatus, attention is invited to said co-pending application. The following brief outline will be sufficient, however, to explain the association and operation of the kerf-cutter with such an apparatus, and for this purpose, before describing the kerf-cutter specifically, its adaptation and use in combination with mining machinery shown in Figs. 1 and 2, will be described.

The method carried out with the use of the illustrated apparatus contemplates first cutting the kerf in the side walls of a mine vein, such as A, dislodging the material after the kerf has been cut, and conveying the same in a more or less continuous operation into a mine car 5, which is adapted to be hauled over the track system 6 of the mine to and from the mining apparatus.

90

100

The kerf-cutter is shown, as at 7 in Fig. 1, in an inactive position to where it has been moved from kerf-cutting position relative to the mine wall A so as to be out of the way of the material-dislodging apparatus. This material-dislodging apparatus embodies in its construction, a plurality of fingers 8, best illustrated in Fig. 2. These dislodging fingers are all supported in their proper position upon a supplemental frame 9 with the frame pivotally secured to a main frame 10 so that the same may swing in an arc as it progresses along the wall of the mine vein in dislodging the material. The main frame 10 is equipped with traction means, such, for instance, as track-laying mechanism 11, so that the entire apparatus including the kerf-cutter 7, may be progressively advanced toward the wall of the mine vein A as the mining operation proceeds. Of course, the traction means is also adapted to transport the machinery to different locations within the mine when occasion demands.

Supported by the main frame 10 to the rear thereof is a hopper 12 which is equipped with a rearwardly extending chute 13. Extending into the hopper 12 and along the chute 13 is a continuous conveyer belt 14. The extended chute 13, together with the conveyer belt 14, is adapted to be introduced through one end of the mine car 5 so as to deliver material thereto from the hopper 12. The material dislodged from the mine vein A is delivered to the hopper 12 by the belt conveyer 15 associated with the dislodging mechanism. The belt 15 empties the material into a hopper 16 from which it is collected by a conveyer belt 17 and dumped into the hopper 12. The relative co-operative relationship of the conveyer belt 15 and the dislodging mechanism is so arranged as to automatically collect the material as it is dislodged and carry it rearward to the waiting mine car 5 without undue loss of time.

Owing to the fact that the car 5, when filled, will necessarily have to be hauled away and during the interim between the time that a new car is brought up, the conveyer belt 14 may be discontinued in operation, the hopper 12 in this connection being of sufficient size to accommodate what material is delivered thereto from the belt 17. The purpose of this arrangement is to make it unnecessary to discontinue the operation of the dislodging mechanism and the conveying apparatus while the mine cars are changed.

To securely anchor the main frame 10, as well as the apparatus associated therewith, which remain stationary during the mining operation, except for that time which requires the same to be advanced forwardly, a suitable roof jack 18 is employed.

The means for operating the material-dislodging apparatus comprises a fluid pressure mechanism, the distributing pipes of which

are shown at 19 in Figs. 1 and 2. This mechanism includes fluid pressure motors for actuating the dislodging tools 8 and motors for actuating the walking roof jacks 20. These walking roof jacks 20 advance the supplemental frame 9 and also anchor the apparatus in advancing stages so that the cutting operation of the tools may be carried on. This operation is all clearly described in detail in the co-pending application heretofore identified.

In Fig. 1 the initial position of the dislodging mechanism and the gathering conveyer 15 is shown in dotted lines, the full lines representing the position of the dislodging and gathering apparatus while in operation along the mine wall. When the coal to be cut is comparatively hard making it desirable to cut a kerf intermediate the floor and the roof to facilitate dislodging of the coal, the dislodging and gathering apparatus may be moved rearwardly of its dotted line position in Fig. 1 and the kerf-cutter moved to its initial position approximately where the frame 9 is shown in dotted lines. While the cutter is being rotated or driven by the motor 42, the motor 41 may be also operated to effect swinging feeding movement of the cutting tool bodily in an anti-clockwise direction so as to cut a kerf intermediate the sets of dislodging tools and distant therefrom and in advance of the gathering mechanism. It should be particularly noted that feeding of the mechanism is effected by the electric motor 41 independently of the driving of the cutting mechanism by means of the electric motor 42. The rotation of the cutter may therefore be at any desired speed and the feed may be varied in accordance with the hardness of the coal. It should also be noted that the feeding movement of the cutting mechanism is independent of the swinging or feeding of the dislodging mechanism because the swinging of the dislodging mechanism and the gathering device is effected by the motor 80 on the base frame 10 connected to the rope winding mechanism 21.

Some coal veins have partings or dirty bands and these occur at various elevations, thicknesses and inclinations or dips. The kerf-cutter shown is well adapted to cutting out the foreign material from such partings in advance of the gathering device 15, such foreign material being deposited on the floor of the mine chamber adjacent the base of the mine wall where it may be shoveled onto the conveyer 15; or if the machine is stripped of the dislodging mechanism as contemplated in the inventor's co-pending application, Serial No. 4,768, filed January 26, 1925, for an improvement in loading machines, as a division of Serial No. 346,903, filed December 23, 1919, for an improvement in mining and loading apparatus, the foreign material cut out from the partings or dirty bands may be scooped

up by the inclined scoop 81 at one side of and in advance of the conveyer 15, as shown in Fig. 1. To adjust the kerf-cutter in accordance with the positions of the partings, the 5 entire self-contained kerf-cutting apparatus may be elevated by means of the pairs of racks at opposite sides of the supporting framework. This adjustment of the kerf-cutter in elevation may be effected by power- 10 operated mechanism, including the electric motor 32 shown in Fig. 2. The inclination of the kerf-cutter may be adjusted on the transverse axis of the trunnions 25, 26 by turning the wheel 62. The cutter may also 15 be adjusted in inclination on the axis of the trunnions 37, 38 by turning the wheel 60. The longitudinal axis on the trunnions 37, 38 is substantially at right angles to the transverse axis on the trunnions 25, 26. The 20 supports 23, 24 have suspended therefrom what is in reality a self-contained mining machine which irrespective of the position to which it has been adjusted will always cut a plane kerf since the axis of feeding movement at the center of the disc 39 is always at 25 right angles to the plane of the kerf-cutter and to the plane of the kerf which is cut in the mine wall.

The above will be sufficient to describe the 30 co-operative relationship of the kerf-cutter 7 to the mining machine illustrated, at least for the purpose of clearly explaining the use of the kerf-cutter, and the remainder of the 35 description will now be devoted to the construction of the kerf-cutter, per se.

Projecting forwardly above the main frame 10 of the mining apparatus and in spaced parallel relation are a pair of arms 23 and 24 which are trunnioned at 25 and 26 to the diametrically opposite sides of the circular frame 27 of the kerf-cutter. These arms are pivotally mounted, as illustrated in Figs. 1 and 2, to the upper ends of the rack bars 28 and 29, which, in turn, extend vertically along the 45 guideways 30 and 31 at the sides of the main frame 10 of the mining apparatus.

In Fig. 2 is diagrammatically illustrated mechanism for lifting and lowering these vertical rack bars 28 and 29 so as to adjust the 50 elevation of the spaced arms 23 and 24 in adjusting the elevation of the kerf-cutter. This mechanism for lifting and lowering the vertical rack bars 28 and 29 preferably comprises a motor 32 which is connected by a 55 shaft 33 to gearing suitable for the purpose, meshing with the rack teeth of said rack bars. A transverse shaft 34, actuated by the motor 32, extends across the machine frame a sufficient distance above the conveyer belt 60 17 so as not to interfere with the passage of material traveling thereon from the hopper 16 to the hopper 12. On the side of the machine frame opposite the longitudinal shaft 33 and also extending longitudinally is a 65 shaft 35 which transmits a drive from the

transverse shaft 34 to the gearing for operating the vertical rack bars corresponding to those designated 28 and 29, on opposite sides of the machine. The starting, stopping and reversing of the electric motor 32 is all that 70 is necessary to regulate the elevation of the arms 23 and 24 and the kerf-cutter carried thereby.

Referring now particularly to Fig. 3, the ring 27 encloses the inner ring 36 which is 75 trunnioned at 37 and 38 at diametrically opposite sides of the kerf-cutter frame at right angles to the trunnions 25 and 26. Rotatably mounted within the inner ring 36 is a circular frame 39, the ring 36 having an annular bearing 39' therefor. Depending from the disc frame 39 is an annular frame 40 for carrying two electric motors 41 and 42. The motor 41 is connected by the worm gear 43 to the pinion 44 which meshes with the 80 annular gear 45 at the lower portion of the ring 36.

Extending forwardly from the depending frame 40 is a tubular frame 46 which carries at its outer end the gear box 47 for enclosing 85 the sprocket wheel 48 in a closed chamber 49 which may be filled with lubricating material. The sprocket wheel 48 is mounted on the shaft 50 which extends along the tubular frame 46 to the gear 51, which meshes with a pinion 90 52 on the shaft of the motor 42.

Mounted on the gear box 47 is a flat disc 53 having a ball race at its periphery for connection by the circular series of balls 54 to the cutter ring 55 carrying the cutters 56. Secured to the outer edge of the disc 53 are 95 spaced-apart annular plates 57 and 58 in the planes of the upper and lower surfaces of the disc 53. These annular plates are of sufficient width to completely cover the cutter-ring 55 and the sprocket gear notches 59 therein, to prevent any dust or dirt from reaching the ball-bearings. The lubricating material within the chamber 49 will, however, be thrown by centrifugal force from 100 the sprocket gear 48 to the ball-bearing enclosure for lubricating these parts.

From the above description, it will be readily seen that the cutting drive for the cutters 56 of the kerf-cutter may be effected directly from the motor 42 through the medium of the shaft 50.

During the cutting operation of the kerf-cutter, the same is progressively moved forward by the motor 41 and the driving connection between the same and the gear 45 meshing with the pinion 44. This motor 41 may also be used as the motive power for swinging the kerf-cutter back to its initial 115 position after the cutting operation thereof has ceased.

Adjusted elevation of the kerf-cutter may be effected, as previously explained, through the medium of the rack bars 28 and 29, raising and lowering the arms 23 and 24. How- 120 125 130

ever, other adjustments of the kerf-cutter are desirable, which accounts for the trunnions 25 and 26 as well as those at right angles thereto indicated at 37 and 38.

5 After the kerf-cutter shown in Figs. 3 and 4 has been adjusted in elevation by operating the motor 32 shown in Fig. 2, such kerf-cutter may also be adjusted in inclination either on the axis of the trunnions 25 and 26, to incline the kerf-cutter up or down toward the mine wall longitudinally in advance of the mining and loading machine, or on the axis of the trunnions 37, 38 to incline the kerf-cutter up or down in the direction in which 10 the dislodging mechanism is moved. By turning the wheel 60 mounted on the bracket 61, the whole kerf-cutting machine may be tilted on the axis of the trunnions 25 and 26. By turning the wheel 62, the ring 36, together 15 with the kerf-cutting mechanism mounted thereon, may be tilted on the axis of the trunnions 37, 38. It should be noted that the wheel 62 is free to turn in the bracket 63 which is connected to the ring 36. The 20 wheel 62 is provided with a screw-threaded rod 64 which is screw-threaded through the bracket 65 on the ring 27 a short distance from the trunnion 38. The looseness of the turning connection at 66 may be relied upon 25 to permit relative tilting movements between the ring 36 and the ring 27.

The wheel 60 is mounted loosely for turning movements in the bracket 61 which is attached to the arm 24. A screw-threaded rod 30 70 extends upwardly from the wheel 60 and is screw-threaded through the bracket 71 which is attached to the outer ring 27. The looseness of the connection between the rod 70 and the bracket 61 may be relied upon to 40 permit of the desired tilting of the entire kerf-cutter on the axis of the trunnions 25 and 26.

45 It should be particularly noted that the plane of the kerf-cutter is at all times substantially at right angles to the upright axis of the arcuate swinging movement of the frames 40 and 46. It is therefore obvious that irrespective of the adjustment of the kerf-cutter, whether to one side or to the 50 other, or whether up or down, the kerfs cut will always be in a plane and such kerfs will be of substantially the same thickness throughout, there being no tendency to cut a conical kerf on account of the adjustment 55 of the inclination of the kerf-cutter.

It will also be seen by referring to Figs. 1 and 2 that the center of the disc 39 is approximately in vertical alignment with the axis of the ring-like mounting 22 which 60 swings the supplemental frame 9 so that the inner ends of the kerfs will be approximately in vertical alignment with the paths of travel of the material dislodging tools on the end of the supplemental frame 9. The axis on 65 which the kerf-cutter is swung will always be

shifted to one side or the other or forwardly or backwardly, in accordance with the adjustment on the two sets of trunnions, because the kerf-cutter is a self-contained mining machine wherein the plane of the kerf cut always remains at right angles to the feeding axis extending through the disc 39 at the center thereof and at right angles thereto. 70

Obviously those skilled in the art may make 75 various changes in the details and arrangement of parts without departing from the spirit and scope of the invention as defined by the claims hereto appended and it is desired therefore not to be restricted to the precise construction herein disclosed. 80

Having thus fully disclosed an embodiment 85 of the invention, what is desired to be secured by Letters Patent of the United States is:

1. In a mining machine, the combination 90 with a supporting frame, of a ring trunnioned on said frame on a horizontal transverse axis, an additional ring trunnioned on said first-named ring on a horizontal longitudinal axis, a circular plate mounted in a circumferential bearing in said additional ring, a 95 motor mounted on said circumferential plate, an annular gear on said additional ring, mechanism between said motor and said annular gear for rotating said circular plate relatively to said additional ring on an axis 100 at the center of the plate and at right angles thereto, a kerf-cutter, an extension from said circular plate to carry said kerf-cutter for bodily movement with said plate, an additional motor connected to said plate, mechanism between said additional motor and said kerf-cutter to drive the latter, means for adjusting the position of said additional ring and the parts carried thereby, relative to said 105 supporting frame to vary the inclination of the kerf-cutter up or down longitudinally, and means for adjusting the relative positions of the said tool rings on the longitudinal trunnion to vary the inclination of the kerf-cutter up or down transversely. 110

2. In a mining machine, the combination 115 with a supporting frame, of supplemental supporting mechanism mounted on said supporting frame for adjustment in elevation, a ring frame pivoted to said supplemental supporting mechanism on a horizontal transverse axis, a second ring frame pivoted to said first-named ring frame on a longitudinal axis extending transversely of said first-named axis, kerf-cutting mechanism mounted on 120 said second ring frame for rotary feeding movement relatively thereto, means for adjusting the elevation of said supplemental supporting mechanism to vary the elevation of said kerf-cutting mechanism, means for adjusting said first-named ring frame on said first-named transverse axis, additional means for adjusting the relative positions of the two ring frames on said longitudinal axis, and means for operating said kerf-cutting 125 130

- mechanism including the feed thereof by rotating the same relatively to said second ring frame.
3. In a mining machine, the combination with a supporting frame, of a kerf-cutter, a support for said kerf-cutter comprising a circular plate, a circular frame having an annular bearing for said circular plate, an electric motor mounted on said support to move bodily therewith, connections between said motor and said kerf-cutter to drive the same, an annular gear on said circular frame, and connections between said motor and said annular gear for rotating said circular plate in the annular bearing in said circular frame.
4. In a mining machine, the combination with a supporting frame, of a ring pivoted thereto on a transverse axis, a second ring concentric to said first-named ring and pivoted thereto on a longitudinal axis, a kerf-cutter, a frame for supporting said kerf-cutter and mounted in an annular bearing in said second-named ring, a motor on said last-named frame to move bodily therewith, connections between said motor and said kerf-cutter for driving the latter, means between said motor and said second-named ring for swinging the kerf-cutter to effect feeding movement thereof, means for adjusting the outer ring on the said transverse axis relative to said first-named supporting frame, and means for adjusting the inner ring relative to the outer ring on the longitudinal axis, the adjustment on the transverse axis varying the inclination of the kerf-cutter longitudinally and the adjustment on the said longitudinal axis varying the inclination of the kerf-cutter laterally.
5. In a mining machine, the combination with a tool support comprising concentric rings each tiltable on an axis transverse relative to the other, of a cutting tool, means for swinging said cutting tool relatively to said support on an axis at the center of and at right angles to the plane of one of said rings, and a motor for driving said cutting tool.
6. In a mining machine, the combination with a main frame, of a kerf-cutter and universally adjustable supporting mechanism for said kerf-cutter comprising concentric rings between said main frame and said kerf-cutter.
7. In a mining machine, the combination with a main supporting frame, of a kerf-cutter, supplemental supporting mechanism comprising concentric rings with the inner frame pivoted to the outer frame and the latter pivoted to said supporting frame, the pivotal axes being at right angles to each other, and means for operating the kerf-cutter in a plane at right angles to its feeding axis.
8. In a mining machine, the combination with a main frame comprising horizontal spaced-apart bearing arms both at substan-
- tially the same elevation, of a supplemental frame trunnioned between said arms for adjustment on a horizontal transverse axis and for suspension in elevated position, kerf-cutting mechanism carried by said supplemental frame, means for adjusting said supplemental frame on said transverse axis to vary the inclination of the kerf-cut by said kerf-cutting mechanism, and means for operating said kerf-cutting mechanism including swinging movement of the rear portion thereof between said trunnions to secure a feeding movement always approximately at right angles to a plane extending through the kerf cut by said kerf-cutting mechanism.
9. In a mining machine, the combination with a main frame, of a supplemental frame mounted thereon, power-operated means for adjusting the elevation of said supplemental frame, self-contained kerf-cutting mechanism for cutting a plane kerf, a universally adjustable support between said supplemental frame and said kerf-cutting mechanism, and means for operating said kerf-cutting mechanism including swinging feeding movement thereof on an axis permanently at right angles to a plane extending through the plane kerf cut by said kerf-cutting mechanism.
10. In a mining machine, the combination with a supporting frame, of a plane chain kerf-cutter, of an auxiliary frame having a circular bearing within the boundary thereof, a cutter carrying frame for said kerf-cutter, a circular extension on said cutter carrying frame fitting into said circular bearing within the boundary of said auxiliary frame, and means for operating said kerf-cutter including the feed thereof by rotating said circular extension in said circular bearing.
11. In a mining machine, the combination with a plane kerf-cutter, of a frame for supporting the same and to move bodily therewith during feeding travel, mechanism supported solely on said frame for driving said kerf-cutter, a second frame, an annular bearing between said first-named frame and said second frame, a motor on said first-named frame, transmission gearing between said motor and said second-named frame to effect swinging feeding movement of said cutter on an axis at right angles to the plane of said kerf-cutter.
12. In a mining machine, the combination with a frame, of a flat circular extension at one end of said frame, a kerf-cutter mounted on the other end of said frame to move bodily therewith, means on said frame for driving said cutter, a supporting frame having an annular bearing for receiving said circular extension from below for suspending said first-named frame, and means for swinging said first-named frame on an axis extending through the center of said annu-

lar bearing and located at right angles to the plane kerf cut by said cutter.

In testimony whereof I have signed my name to this specification on this 13th day of October, A. D. 1927.
